COMBINED ASH TRAY AND CIGARETTE SUPPORT

Eric Wedemeyer, Floral Park, N. Y., assignor to Hamilton Art Metal Corporation, New York, N. Y., a corporation of New York

Application May 20, 1954, Serial No. 30,573

Term of patent 14 years

(Cl. D85—2)

Fig. 4.

Fig. 1 is a side view of a combined ash tray and cigarette support, showing my new design, the other side being like the side shown;

Fig. 2 is a front view of the combined ash tray and cigarette support shown in Fig. 1, with a portion of the tray cut away, the rear view being like the front view;

Fig. 3 is a top plan view thereof; and

Fig. 4 is a perspective view thereof.

I claim:

The ornamental design for a combined ash tray and cigarette support, substantially as shown and described.
